UNITED STATES PATENT OFFICE.

FERDINAND HANFF, OF BERLIN-CHARLOTTENBURG, GERMANY, ASSIGNOR TO SIE-MENS-SCHUCKERTWERKE GESELLSCHAFT MIT BESCHRÄNKTER HAFTUNG, OF SIE-MENSSTADT, NEAR BERLIN, GERMANY, A CORPORATION OF GERMANY.

MEANS FOR PRODUCING VARNISHED WIRES.

Application filed November 23, 1925, Serial No. 70,879, and in Germany December 1, 1924.

My invention relates to a method of producing varnished wires.

In the manufacture of varnished wires the coating of varnish is applied successively in a plurality of layers. After the application of each layer the wire is passed through a drying oven in which the varnish or the like is baked. Hitherto this method has been carried out in such a manner that the wire was passed in succession through the apparatus for applying the layers of varnish and then through the drying oven, this process being repeated several times until the coating had attained the necessary thickness. The same wire is hereby repeatedly led back into the oven or furnace over guide pulleys.

The principal drawback of this method resides in the fact that the inner layers of varnish become excessively brittle owing to the repeated burning on or firing while the outer layers sometimes remain sticky. It has therefore been proposed to dry the wire in a number of heating channels or passage-ways kept at different temperatures, for instance in such a manner that the temperature of the heating channels or flues increases from channel to channel. In reducing these proposals to practice the hitherto customary oven or furnace constructions were, however, not abandoned altogether. The heating channels through which the wire passes successively were arranged closely side by side. In this manner the production of a definite temperature difference between the individual channels was rendered difficult.

These known methods fail altogether in the manufacture of varnished wire of very small diameters because it is necessary to deflect the wire in return bends by means of guide rollers when it issues from one heating channel in order to conduct it into the next. The wire is not able to drive these guide rollers without becoming unduly stretched or broken. To drive the guide rollers by an auxiliary power cannot be recommended because even minute deviations in the angular speed or the diameter of the guide rollers already cause an excessive tension or sagging of the wire. The repeated bending and straightening of the wire at the various points of deflection is, furthermore, detrimental for the material of the wires and the coating of varnish.

My invention eliminates these drawbacks

in the following manner. The heating channels or passage-ways in which the wire is dried are, at least generally, located in axial alignment in order to reduce the number of bends in the wire as far as possible. The heating channels traversed by a wire are furthermore located in two or more drying stoves or furnaces which are separated from one another, in order to facilitate the adjustment of the various temperatures.

The apparatus for applying the varnish or the like may be supplied with varnishes of different composition, consistency or color, in order to obtain a wire finished most suitably for the purpose for which it is destined.

In the drawing affixed hereto

Fig. 1 is a sectional elevation of a plant suitable for carrying out my method.

Fig. 2 a plan of the same and

Fig. 3 a sectional elevation of a slightly modified construction.

In Figs. 1 and 2 of the drawing a device or apparatus for carrying out the method is illustrated in which all successive heating ducts are located in one substantially straight line. In this embodiment the horizontal arrangement of the ducts has been chosen. The apparatus illustrated by way of example serves for varnishing twelve wires simultaneously and drying or baking the same in individual heating ducts.

Referring to Figs. 1 and 2, *a* is a frame upon which are rotatably located the reels *b* which hold the wire. The wires *c* unwound from the reels pass over the guide rollers *d* into the varnish container or tank *e*₁ in which a coating of varnish is applied to them. They then travel through the individual heating ducts *f*₁ of the apparatus A and after issuing from those ducts they pass through the second varnish container *e*₂ and receive a second coating of varnish. From here they pass through the individual heating ducts *f*₂ of the apparatus B and after issuing therefrom they receive a third coating of varnish in the varnish tank *e*₃ and so on. After leaving the last group of heating ducts the wires are conducted over guide roller *l* on to the winding reels *m* rotatably located upon the frame *n*. The drive of the winding reels is not illustrated for the sake of simplicity being known to those skilled in the art. The heating ducts, of which only three, *f*₁, *f*₂, *f*₃, are shown in series, are of different lengths and the length

of successive ducts increases in the direction of the travel.

The guide rollers *d* and *l* may be omitted provided the reels *b* and *m* are placed at the 5 level of the heating ducts.

- The heating of such channels, ducts or passage-ways may be effected in any suitable manner, for instance by a gas flame or by electric resistances *o* located in the walls of 10 the heating ducts. Electric heating is particularly suitable because the temperature may then be easily and accurately adjusted. Directly above the openings or inlets and outlets of the heating ducts are located hoods 15 *h* for catching the issuing varnish vapors. The vapors caught are conducted along the outside of the ducts at *i* and pass into the flue or conduit *j* adapted to be throttled by a damper or valve *k*. The hot vapors transmit 20 part of their heat to the heating ducts while passing along their outside and thus prevent radiation and therefore save heat. Their temperature remains, however, high enough to set up the necessary draft in the discharge 25 conduit *j*. With this arrangement a special fan for sucking off the vapors is rendered superfluous.

Another plant for practicing my improved method is illustrated in Fig. 3 of the drawing. In this plant the heating ducts *f*₁ to 30 *f*₆ are all of equal length but their temperature rises in steps in the direction of travel of the wire. In the ducts *f*₁ there prevails the lowest temperature and in the ducts *f*₆ 35 the highest. In order to shorten the length of the apparatus or plant two heating ducts are located above each other or side by side in one frame. Each wire first traverses the ducts *f*₁ to *f*₅, is then reversed by the guide 40 roller *p* and passes through the ducts or

chambers *f*₄ to *f*₆. Otherwise the design of the plant corresponds with that illustrated in Figs. 1 and 2.

Instead of locating the heating ducts horizontally, as illustrated, and thus to pass the 45 varnished wires through the plant horizontally, a vertical or oblique arrangement of the ducts may be chosen.

Various modifications and changes may be made without departing from the spirit and 50 scope of the invention, and I desire, therefore, that only such limitations shall be placed thereon as are imposed by the prior art.

I claim as my invention:—

1. Machine for varnishing wires having a 55 plurality of varnishing devices and baking ducts arranged alternately and substantially in a straight line, the length of the individual ducts increasing in the direction of the wire travel.

2. Machine for varnishing wires, having a plurality of separate baking ovens containing baking ducts, and varnishing devices alternately arranged with said ducts in a straight line, the length of the individual 65 ducts increasing in the direction of the wire travel, successive baking ducts being disposed in separate baking ovens.

3. Machine for varnishing wires, having a plurality of separate baking ovens containing baking ducts, and varnishing devices alternately arranged with said ducts in a straight line, the length of the individual 70 ducts increasing in the direction of the wire travel, successive baking ducts being disposed 75 in separate baking ovens and means on said ovens for conducting the hot vapors issuing from said ducts around the outside thereof.

In testimony whereof I affix my signature.
FERDINAND HANFF.
